UNITED STATES PATENT OFFICE

146,620

DESIGN FOR A PROJECTION LAMP
HOUSING

Jean O. Reinecke, Oak Park, Ill., assignor to Bell
& Howell Company, Chicago, Ill., a corporation
of Illinois

Application July 13, 1946, Serial No. 131,564

Term of patent 14 years

(Cl. D61—1)

To all whom it may concern:

Be it known that I, Jean O. Reinecke, a citizen of the United States, residing at Oak Park, in the county of Cook and State of Illinois, have invented a new, original, and ornamental Design for a Projection Lamp Housing, of which the following is a specification, reference being had to the accompanying drawing, forming a part thereof.

In said drawing:

Figure 1 is a side elevation of a projection lamp housing embodying my new design;

Figure 2 is a rear elevation of the same;

Figure 3 is a top plan view of the same; and

Figure 4 is a front elevation of the same.

I claim:
The ornamental design for a projection lamp
housing, as shown.

JEAN O. REINECKE.
